UNITED STATES PATENT OFFICE

ALFRED D. ANTOINE, OF CHICAGO, ILLINOIS, ASSIGNOR TO ADVANCE MACHINE COMPANY, OF CHICAGO, ILLINOIS, A CORPORATION OF ILLINOIS

COIN-CONTROLLED MECHANISM FOR VENDING MACHINES

Application filed October 28, 1929. Serial No. 402,827.

This invention relates to improvements in coin controlled mechanism particularly adapted, though not necessarily limited in its use, in connection with vending machines of the type whereby when a coin of a predetermined denomination or size is deposited therein in the machine may be actuated through the instrumentalities of the coin.

One of the particular objects of the invention is to provide coin controlled mechanism of this character which will be operated only with a predetermined plurality of coins, thereby necessitating the deposit of more than one coin into the machine before the mechanism will be rendered active.

A further object is to provide in a machine of this character improved means for preventing the operation thereof by a plurality of coins, one of which is either in excess of the diameter of the proper coin, or is too large or too thin, or too soft with relation thereto.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a rear elevation of a coin controlled mechanism of this character constructed in accordance with the principles of this invention, and showing the parts in their normal position.

Figure 2 is a view similar to Figure 1, with parts omitted and parts broken away, showing the mechanism in the same position as in Figure 1.

Figure 3 is a view similar to Figure 2, with parts omitted and parts broken away, showing the position the parts will assume when the proper coins have been inserted and the detector mechanism properly adjusted or moved thereby, so as to permit the operation of the mechanism.

Figure 4 is a view similar to Figure 3, showing the parts in a further advanced position.

Figure 5 is a detail top plan view of the detector mechanism.

Figure 6 is a detail sectional view taken on line 6—6, Figure 3.

Figure 7 is a detail sectional view taken on line 7—7, Figure 8.

Figure 8 is a view of Figure 7 taken from the right hand side thereof.

Figure 9 is a detail sectional view with parts omitted, taken on line 9—9, Figure 3.

This improved detector mechanism is more particularly adapted for use with the check controlled mechanism disclosed in my co-pending application, Serial No. 210,768, and only such part of the mechanism with which this detector mechanism cooperates, will, however, be described. Suffice it to say, that the mechanism herein disclosed embodies a check carrier 15 which is mounted upon a shaft 16 for rotation therewith, and the check carrier is provided with a plurality of check seats 17—18, the seat 17 being adapted to receive a coin or check of a larger size or diameter than the coin or check adapted to be received in the seat 18.

There is preferably provided a partition 19 between the two seats and this partition is preferably tapered as shown, for a purpose to be hereinafter set forth. The bottom 20 of the seat 17 as well as the bottom 21 of the seat 18, are inclined towards the adjacent wall of the partition so as to insure the proper positioning of the coins or checks 22—23 respectively therein and so as to also cause the coins to be inclined towards each other at their outermost points, as shown more clearly in Figure 9, for a purpose to be set forth.

The partition 19 serves the purpose of assisting in directing and positioning the coins in the respective seats.

Pivotedly mounted adjacent the path of movement of the coins in their seats and preferably by one end thereof as at 24, is a detector member which preferably embodies two members 25—26, both mounted upon the same pivot 24, and having their adjacent side faces contacting. The member 26 is provided with a laterally projecting flange 27 and the member 25 is provided with a similar flange 28, the flanges being disposed one adjacent the other for the reception of a fasten-

ing device 29 preferably in the form of a coin carrier 15 for rotation therewith in a screw by means of which the two members 25—26 may be relatively adjusted one with relation to the other. A lock nut 30 may be provided on the screw 29.

5 One of the members, preferably the member 26 is provided with a slot 31 and a screw 32 passes through the slot and has threaded engagement with the member 25 so that by loosening the screw 32 and adjusting the 10 screw 29 the members 25—26 may be adjusted with respect to each other, and when adjusted the screw 32 may be tightened to assist in holding the members in their adjusted position.

15 Carried by the member 25 is a roller 33 which projects laterally therefrom and the roller is provided with a recessed portion 34 in its periphery, the walls 35 of the recessed portion being inclined or beveled, for a purpose to be set forth. This roller 33 is mounted to rotate freely upon a trunnion 36 carried by the member 25.

20 A spring 37 is connected by one end as at 38 to the detector member and is anchored by its other end as at 39 to a fixed support, and the spring tends normally to move the detector member in a direction about its pivot 24 so that when the coins in the seats 22 and 23 of the check or coin carrier 15 are advanced, the peripheral edges of the coins will engage the roller 33 and if the coins are of proper size and denominations, the detector member will be moved about its pivot 24 to 30 permit the check carrier 15 and the coins carried thereby to be advanced. The detector member is provided with a flange 40 having an opening 41 therein and which opening, when the detector member is properly positioned will be in a position to permit a laterally projecting flange 42 on a member 43 to pass through the opening, so that the check carrier 15 with the coins therein may be moved from the position shown in Figure 2, 40 to the positions shown in Figures 3 and 4.

45 When, however, coins of improper size are seated in the check seats in the check carrier, the detector member will not be shifted properly and the opening 41 will not be properly located to receive the flange 42 of the member 43.

50 If a check or coin of a smaller diameter than the proper coin is placed in the seat, the edge of the flange 42 will engage the flange 40 on one side of the opening 41. If however, a coin or check of a larger diameter than the proper coin is inserted in the check seat then the detector member will be positioned so that a portion of the flange 40 on 60 the other side of the opening 41 will be in the path of movement of the edge of the flange 42 on the member 43. In either instance the check or coin carrier will be locked against advancing movement.

65 The member 43 is connected with the check

any suitable manner, such as by means of a hub 44 which is secured to the shaft 16.

A spring 45 is connected by one end as at 46 with the member 43 and is anchored by its other end as at 47 and tends normally to move the member 43 with the flange 42 to the position shown in Figures 1 and 2. When, however, the member 43 is moved to the position shown in Figures 2 and 4, under the conditions heretofore set forth, the spring 45 will be placed under tension so as to return the parts to their normal position.

70 The coins will be advanced from the position shown in Figures 3 and 4 to a position 80 that the coin seats will be inverted to allow the coins to drop therefrom, after which and upon return movement of the coin carrier 15 the coins will be discharged into the machine by the engagement of a shoulder 48 on the coin carrier with the edge of the coin to force the coin against a pivotally mounted member 49 that carries a retaining pawl 50, in a manner to actuate the pawl 50 to release a disc 51 which is connected with the parts of 90 the mechanism that are to be set into motion, the disc 51 being moved in an advancing direction by means of a pawl 52 pivotally mounted as at 53 and connected with the member 43 for movement therewith, in a 95 manner similar to that set forth in the application herein referred to, but which tripping mechanism and the means for rotating the disc 51 constitutes no part of the present invention. Suffice it to say that the pawl 50 is controlled by a spring 54 which tends normally to move it in a direction to co-operate with teeth 55 on the disc 51.

100 It is thought that the operation of this device will be clearly understood from the foregoing, but briefly stated it is as follows.

105 The normal position of the parts are as shown in Figures 1 and 2, and when the two coins of a proper size and denomination are placed respectively in the seats 22 and 23 of the coin carrier 15, the shaft 16 is rotated by means of a suitable handle (not shown but well known in this art) so as to move the member 43 in the direction indicated by the arrow in Figure 2.

110 By the time the end of the flange 42 assumes a position in close proximity to the flange 40 on the detector, the coins in the coin seats will have shifted the detector member to a position so that the flange 42 can pass 115 through the opening 41 in the flange 40 of the detector. The edges of the coins will then pass into a position to engage the roller 33 on the detector as shown in Figures 3 and 9. If two coins of the proper size and thickness are placed in the coin seats their combined width will be sufficient to cause the outer peripheral edges of the two coins to engage the respective inclined walls 35 of the recess 34 in the roller 33, with 120 125 130

the result that the coins being forced against this roller will cause the detector to be shifted to properly position the member 43.

If one of the coins is of an improper diameter or thickness, the peripheral edge of only one of the coins will engage the respective inclined wall 35 of the recess 34 and owing to the fact that the engagement of a single coin with the roller 33 will not be sufficient to shift the detector member against the stress of the spring 37, the mechanism will not be unlocked and the detector will not be shifted to a position so that the flange 42 on the member 43 can pass through the opening 41.

The edge of the flange 42 will engage the flange 40 in either one or the other sides of the opening 41 according to the nature of the spurious coin placed in the coin seat. That is, if it is of a greater diameter than the detector will be shifted a greater distance than if the spurious coin is of a smaller diameter than the proper coin.

If the spurious coin or token which is inserted in one or both of the check seats is of softer material than that from which the proper coins are formed, then the stress of the spring 37 will cause the roller 33 to crush the improper coin and the mechanism will not be unlocked.

Likewise when a single coin instead of two coins, is placed within one or the other of the coin seats of the coin carrier 15, the mechanism cannot be operated and the detector member cannot be shifted, for the reason that if only one coin is present, and even though of the proper size and thickness, the peripheral edge thereof will engage one of the inclined walls of the roller 33 and the coin will be shifted in its seat laterally and the edge of the coin will not be in a proper position to shift the detector member 43.

If, however, and as before set forth, the proper coins 22 and 23 are inserted in the coin seat, the detector member will be shifted to a proper position to permit the flange 42 to pass through the opening 41.

The adjusting means between the two members constituting the detector is provided so as to compensate any inaccuracies in manufacture and also to provide a means whereby the mechanism may be properly adjusted to be operated by a predetermined plurality of coins.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. Coin controlled mechanism embodying a coin carrier having an opening for receiving and simultaneously holding a plurality

of coins face to face, locking means controlled by the combined action of said coins for controlling the actuation of said carrier, and a roller operatively connected with said locking means and adapted to be engaged by the peripheral edges of said coins and shifted thereby to render the locking means inactive to permit actuation of the coin carrier. 70

2. Coin controlled mechanism embodying a coin carrier having an opening for receiving and simultaneously holding a plurality of coins face to face, locking means controlled by the combined action of said coins for controlling the actuation of said carrier, and a roller operatively connected with said locking means and adapted to be engaged by the peripheral edge of said coins to be shifted thereby to render the locking means inactive, said roller having a portion reduced in diameter into which the edge of a coin will enter to prevent rendering the locking means inactive when an insufficient number of coins is deposited in the said opening in the coin carrier. 75 80 85

3. Coin controlled mechanism embodying a coin carrier having an opening for receiving and simultaneously holding a plurality of coins face to face, locking means controlled by the combined action of said coins for controlling the actuation of said carrier, and a roller operatively connected with said locking means and adapted to be engaged by the peripheral edge of said coins to be shifted thereby to render the locking means inactive, said roller having a portion reduced in diameter into which the edge of a coin will enter to prevent rendering the locking means inactive when one or more improper coins is or are deposited in said opening in the coin carrier. 90 95 100

4. Coin controlled mechanism embodying a coin carrier adapted to receive and advance a predetermined plurality of coins into an operative position, a detector member, said member controlling the operation of said carrier, and means operatively connected with said detector member and adapted to be engaged by the peripheral edges of all of said coins and being shiftable only by the combined action of all of said coins to render the coin carrier active to advance the coins further through the mechanism. 105 110 115

5. Coin controlled mechanism embodying a coin carrier adapted to receive and advance a predetermined plurality of coins into an operative position, a detector member, said member controlling the operation of said carrier, and means operatively connected with said detector member and adapted to be engaged by the peripheral edges of all of said coins and being shiftable only by the combined action of all of said coins to render the coin carrier active to advance the coins further through the mechanism, the said means being also operative to cause the action of an 120 125 130

insufficient number of coins in the coin carrier to be ineffective thereupon as regards the shifting thereof.

6. Coin controlled mechanism embodying a coin carrier adapted to receive and advance a predetermined plurality of coins into an operative position, a detector member, said member controlling the operation of said carrier, and means operatively connected with said detector member and adapted to be engaged by the peripheral edges of all of said coins and being shiftable only by the combined action of all of said coins to render the coin carrier active to advance the coins further through the mechanism, the said means being also operative to cause the action of an insufficient number of coins in the coin carrier to be ineffective as regards the shifting thereof, by dislocating the coin with respect to its seat in the coin carrier.

7. Coin controlled mechanism embodying a coin carrier having an opening for receiving and advancing a coin, a shiftable controlling member forming with the wall of said opening a space through which the coin is adapted to be passed by the carrier, the peripheral edge of the coin engaging and shifting said member as it passes the latter, and means whereby said member will shift a predetermined improper coin with respect to said carrier to prevent operation of said member by such improper coin in the said opening.

8. Coin controlled mechanism embodying a coin carrier having an opening for receiving and advancing a coin, a shiftable locking member co-operating with the wall of said opening to form a space between which the coin is adapted to be passed by the carrier, a portion of said member being arranged in the path of movement of the peripheral edge of the coin to be engaged and shifted thereby, the said member having a shape to provide an enlargement of a portion of said space, and means for causing the edge of an improper coin to enter the said enlarged portion of the space to prevent operation of the said locking member by such improper coin.

9. Coin controlled mechanism embodying a coin carrier having an opening for receiving a predetermined plurality of coins, and a shiftable locking member co-operating with the wall of said opening to form a space between which the coins are adapted to be passed by the carrier, a portion of said member being positioned to be engaged by the peripheral edges of the coins and operable by the combined thickness of the coins on the carrier, the said portion of said member having a shape to provide an enlargement of a portion of said space and into which enlargement the coins will enter to prevent operation of the said locking member either by the presence of an insufficient number of coins on the carrier, or by a plurality of coins of

improper denomination and size on the carrier.

10. Coin controlled mechanism embodying a coin carrier having an opening for receiving a predetermined plurality of coins, a shiftable locking member co-operating with the wall of said opening to form a space between which the coins are adapted to be passed by the carrier, a portion of said member being positioned to be engaged by the peripheral edges of the coins and operable by the combined thickness of the coins on the carrier, the said portion of said member having a shape to provide an enlargement of a portion of said space, and means for forcing the coins to project into such enlargement to prevent the operation of the said locking member either by the presence of an insufficient number of coins on the carrier, or by a plurality of coins either or both of which on the carrier is of an improper size or denomination.

11. Coin controlled mechanism embodying a coin carrier having an opening for receiving a predetermined plurality of coins, a shiftable control member operable by the combined thickness of the coins on the carrier, a roller carried by said member, said roller co-operating with the wall of said opening to form a space through which the coins are adapted to be passed by said carrier, a portion of the roller being reduced in diameter to form a space into which the coins will enter to prevent shifting of said control member either by the presence of an insufficient number of coins on the carrier, or by a plurality of coins on the carrier of improper size or denomination, and means for forcing such coins into the space formed by such reduced portion of the roller.

12. Coin controlled mechanism embodying a coin carrier having an opening for receiving a predetermined plurality of coins, a shiftable control member operable by the combined thickness of the coins on the carrier, a roller carried by said member, said roller co-operating with the wall of said opening to form a space through which the coins are adapted to be passed by said carrier, a portion of the roller being reduced in diameter to form a space into which the coins will enter to prevent shifting of said control member either by the presence of an insufficient number of coins on the carrier, or by a plurality of coins on the carrier of improper size or denomination, the wall of the space formed by such reduced portion of the roller being inclined and operating to force such coins into the space formed by such reduced portion of the roller.

13. Coin controlled mechanism embodying a coin carrier having openings to receive a predetermined plurality of coins face to face, a partition between such openings, the bottom of said openings inclining towards

the partition to cause the outer edges of the coins to stand in close proximity to each other, a shiftable controlling member, a roller carried by said member and co-operating with the bottom of said openings to form a space through which the coins are adapted to be passed by the carrier, the peripheral edges of the coins engaging the roller, said roller and member being shiftable only by the combined thickness of the coins on the carrier, and means for causing said member and roller to be inoperable by the presence of an insufficient number of coins on the carrier, or by a plurality of coins of improper size, denomination and characteristic on the carrier.

14. Coin controlled mechanism embodying a coin carrier having openings of different depths opposite each other, the bottoms of said openings being inclined with respect to each other to cause the other portions of the coins seated therein to stand in close proximity to each other, a shiftable controlling member, a roller carried by said member and co-operating with the bottoms of said openings to form a space through which the coins are adapted to be passed by the carrier, the peripheral edges of the coins engaging the roller, said roller and member being shiftable only by the combined thickness of the coins on the carrier, and means for causing said member and roller to be inoperable by the presence of an insufficient number of coins on the carrier, or by a plurality of coins of improper size, denomination and characteristic on the carrier.

15. Coin controlled mechanism embodying a coin carrier, a shiftable controlling member, a detector member connected therewith for adjustment one with relation to the other, means for securing said members in their adjusted positions, a roller mounted upon one of the said members, said roller co-operating with the wall of said openings to form a space between which the coins are adapted to be passed by said carrier, said roller and said members being shiftable by the combined width of the coins on the carrier, and means whereby the said roller and members will be maintained against being shifted by the presence of an insufficient number of coins on the carrier, or by a plurality of coins of improper size, denomination and characteristic on the carrier.

16. Coin controlled mechanism embodying a coin carrier adapted to carry a predetermined plurality of tokens into an operative position, a shiftable controlling member forming with a portion of the carrier a space through which the tokens are adapted to be passed by the carrier, the peripheral edge of the tokens engaging and shifting said member as they pass the latter, said member being shiftable only by the combined width of said tokens, and means for

causing the said member to crush or mutilate either one or both of said tokens, if one or both of the tokens is or are not of a proper or predetermined degree of hardness.

In testimony whereof I have signed my name to this specification, on this 24th day of October, A. D. 1929.

ALFRED D. ANTOINE.
